C. R. WASER.
SPHYGMOMANOMETER.
APPLICATION FILED JULY 14, 1914.

1,164,895.

Patented Dec. 21, 1915.

UNITED STATES PATENT OFFICE.

CARL R. WASER, OF PHILADELPHIA, PENNSYLVANIA, ASSIGNOR TO THE PRECISION THERMOMETER AND INSTRUMENT COMPANY, OF PHILADELPHIA, PENNSYLVANIA, A CORPORATION OF PENNSYLVANIA.

SPHYGMOMANOMETER.

1,164,895.

Specification of Letters Patent. Patented Dec. 21, 1915.

Application filed July 14, 1914. Serial No. 850,891.

To all whom it may concern:

Be it known that I, CARL R. WASER, a citizen of the United States, residing at Philadelphia, in the county of Philadelphia and State of Pennsylvania, have invented certain new and useful Improvements in Sphygmomanometers, of which the following is a specification.

My invention is a sphygmomanometer having a tube with a movable section hinged to a fixed section, a valve for closing the end of the fixed section to prevent the escape therefrom of the liquid used therein, and means for holding the valve in the desired position.

In the accompanying drawings, Figure 1 is an elevation of an instrument embodying my invention with part of the scale broken away. Fig. 2 is an enlarged front elevation of a section of the same. Fig. 3 is an enlarged side elevation of a section of the same. Fig. 4 is a top plan view of the tube sections in folded relation with the valve seated on the end of the fixed tube section and a part of the lid shown in section. Fig. 5 is a part sectional side elevation of a section of the construction with the elements in the relation occupied in Fig. 4. Fig. 6 is a longitudinal sectional view taken through the top of the fixed tube section and the valve seated thereon, and Fig. 7 is a vertical longitudinal sectional view taken through the closed case with the instrument folded therein.

In the form of the instrument illustrated in the drawing, the case 1 has fixed to its hinged lid 2 the tube 3 provided with the branch 4, 5 and 6, a stop cock 7 controlling communication between the parts 3 and 5 and a needle valve 8 controlling discharge from the part 3 through the part 6. A pneumatic bulb or pump 9 is connected through the flexible tube 10 with a nipple 11 which is engaged in the branch 5 and a pneumatic cuff 12 is connected through the flexible tube 13 with a nipple 14 which is engaged in the branch 4. A cistern 15 has a neck 16 which is connected by a coupling 17 with the tube 3, the bottom of the cistern being connected by a bend 18 with a tube section 19 and the bend being fixed to the lid 2 as by the clip 20. The top of the tube section 19 has fixed thereon an open clip or shoe 21 having a bearing or bracket 22 fixed to the lid 2, the clip being provided with the forwardly pro-

jecting bearings 23 and the rearwardly projecting bearings 24. A leather ring or gasket 25 is fixed on the open end of the section 19, being engaged by the flange 26 turned in from the top of the clip 21 on the outer edge of the ring. A tube section 27 has fixed on the lower end thereof an open clip or shoe 28 provided with the forwardly projecting bearings 29 hinged to the bearings 23 by the pintles 30 and the rearwardly projecting arm 31 adapted to engage a spring catch 32 fixed on the lid 2. A valve 33 is provided with the bearing 34 which is hinged between the bearings 24 by the pinte 35 passing therethrough, the valve being provided with the arm 36 having the resilient fingers or bifurcations 37 adapted for engaging the section 27 and with the leather washer 38 adapted for engaging the leather ring 25. A spring 39 bears against the valve 33, has the coils 40 on the pinte 35 and the ends 41 fixed to the bearings 24, the spring acting to automatically close the valve on the end of the tube section 19 when the tube section 27 has been folded over and the valve arm 36 bearing on the adjacent end of the tube section to hold it in folded position.

A spring 43 is fastened to the bottom of the case 1 to frictionally engage the valve arm 36, when the lid 2 with the instrument thereon is folded down, the spring acting to securely hold the valve seated on the end of the section 19. In operation, the lid 2 is brought to the elevated position, the valve 33 and tube section 27 are turned to the position shown in Figs. 1, 2 and 3, with the arm 31 engaged by the catch 32 and the tube section thereby held seated on the gasket 25, the cuff 12 is affixed, the valve 7 is opened and the valve 8 closed, the pump 9 is operated to force the mercury from the cistern 15 up the tube sections 19 and 27 until the pulse of the patient is obliterated, the valve 7 is then closed and the valve 8 is opened and the reading of the scale 42 is taken when the pulse is observed. The open character of the front of the clips 21 and 23 provides for continuity in the exposed fronts of the tube sections 19 and 27, permitting the surface of the mercury to be observed substantially throughout its course.

Having described my invention, I claim:—

1. In a sphygmomanometer, a tube hav-

ing sections connected in hinged relation so that they are adapted to engage in registration and to fold relatively, in combination with a valve hinged on one of said sections 5 adapted to be turned to a position exterior to said tube in the registering relation of its sections and to close the section to which it is hinged in the folded relation of the other.

2. In a sphygmomanometer, a tube having sections provided with hinged clips on adjacent ends thereof, and a flap valve hinged on one of said clips adapted to be moved to a position exterior to said sections when in alinement or to be moved, to close 15 an end of the section to which it is hinged when the tube sections are in folded position.

3. In a sphygmomanometer, a tube having sections provided with hinged clips having openings in alinement exposing registering ends of said tube sections and a valve hinged on one of said clips so that it can be turned to a position exterior to said sections in the registering relation thereof, said valve being adapted for closing an end of 25 one of said tube sections in the folded relation thereof.

4. In a sphygmomanometer, a tube having a stationary section and a section movable into and out of registration with said 30 stationary section, in combination with a valve having a hinge exterior to said tube whereby it is adapted to close said stationary section when said movable section is out of registration, and to be removable from 35 said sections to permit registration thereof, and means independent of said valve for locking said sections in registration.

5. In a sphygmomanometer, a tube having sections connected in hinged relation, a 40 flap valve adapted for closing an end of one of said sections, means on said valve engaged by the other of said sections when the latter are in registration, and means com-

prising a spring for locking said sections in registration.

6. In a sphygmomanometer, a case having a lid, a tube section fixed to the lid, a tube section hinged to the fixed tube section, a flap valve having a hinge exterior to the sections whereby it is adapted to close one 50 section in the folded position of the other, and means carried by said case whereby said valve is held seated when said lid is closed.

7. In a sphygmomanometer, a case having a hinged lid, a tube section fixed within the 55 lid, a tube section hinged to the fixed tube section so as to register therewith and fold thereon, a member on the movable section and an interlocking stationary member for holding the movable member in registration 60 with the fixed member, a flap valve hinged exterior to the tube sections and adapted to close the end of the stationary section, and means carried by the case for holding the valve on the end of the fixed section.

8. In a sphygmomanometer, a case having a hinged lid, a tube having sections provided with end clips hinged together to permit one section to be turned relatively to the other stationary section, means for fixing 70 the stationary section to the lid, a latch carried by the lid, a device carried by the movable section for engaging the latch and holding the sections in registration, and a spring pressed valve having a turning axis exterior 75 to the tube and adapted for closing the fixed section in the folded position of the movable section, said valve having means for engaging an end of the folded section and holding it in folded position.

In testimony whereof I affix my signature in presence of two witnesses.

CARL R. WASER.
